LABEL HOLDER FOR ATTACHMENT TO COLLARS FOR MAGNETIC RECORDING TAPE REELS

Jack E. Blackburn, Oakdale, Reginald B. Cass, Maplewood, and Douglas H. Cameron, Stillwater, Minn., assignors to Minnesota Mining and Manufacturing Company, St. Paul, Minn.

Filed Dec. 26, 1973, Ser. No. 427,667

Term of patent 14 years

Int. Cl. D14—99; D20—99
U.S. Cl. D26—14 B

FIG. 1 is a perspective view of a label holder for attachment to collars for magnetic recording tape reels, showing our new design;

FIG. 2 is a top plan view of a label holder of our new design;

FIG. 3 is a bottom plan view of a label holder of our new design;

FIG. 4 is a side elevational view of a label holder of our new design, the other side having the same appearance;

FIG. 5 is an end view of a label holder of our new design, showing the left end of the label holder as shown in FIG. 1;

FIG. 6 is an end view of a label holder of our new design, showing the right end of the label holder as shown in FIG. 1; and

FIG. 7 is a sectional view of a label holder of our new design, taken along the lines 7—7 of FIG. 2.

We claim:

The ornamental design for a label holder for attachment to collars for magnetic recording tape reels, substantially as shown and described.
